WORKTABLE POSITIONING MEANS

John M. Rusnak, West Hartford, Conn., assignor
to Niles-Bement-Pond Company, Hartford,
Conn., a corporation of New Jersey

Application July 20, 1938, Serial No. 220,296

5 Claims. (Cl. 33—181)

This invention relates to precision boring machines and particularly to an improved means for positioning the work supporting table of a boring machine to predetermined locations in directions at right angles to each other and normal to the axis of rotation of the boring tool of the machine.

An object of the present invention is to provide precision locating means for the worktable over a wide range in two directions normal to each other by improved easily operated means facilitating the determination of the positions to which the table is moved and in a manner eliminating the danger of injury to the measuring devices.

A feature of importance of the invention is that the initial setting of the positioning mechanism for successive work pieces is facilitated.

And another feature that is advantageous is that the position determining means for the table do not require the insertion and removal of end measures, all parts of the present indicating and positioning mechanism being retained at all times in position upon the machine.

Another object of the invention is to provide an improved micrometer and operating means and indicating means therefor and also improved means to clamp the micrometer spindle accurately in predetermined adjusted positions.

With the above and other objects in view, the invention may include the features of construction and operation set forth in the following specification and illustrated in the accompanying drawings.

In the accompanying drawings annexed hereto and forming a part of this specification, I have shown the invention embodied in a standard form of vertical boring machine but it will be understood that the invention can be otherwise embodied and that the drawings are not to be construed as defining or limiting the scope of the invention, the claims appended to this specification being relied upon for that purpose.

In the drawings:

Figure 1 is a front elevation of the principal parts of a precision boring machine having the present invention applied thereto.

Fig. 2 is a front elevation on an enlarged scale of the worktable of the boring machine showing the positioning means for the table in one direction.

Fig. 3 is a front elevation in section and on an enlarged scale of some of the parts shown in Fig. 1.

Fig. 4 is a plan view of a portion of the positioning and indicating mechanism for the table shown in Figs. 1, 2 and 3.

Fig. 5 is a plan view of a portion of the oper-

ating mechanism for the positioning mechanism shown in Fig. 4 with the parts in another operative position.

Fig. 6 is a vertical sectional view on the plane of line 6—6 of Fig. 5.

Fig. 7 is a fragmentary sectional elevation on an enlarged scale of the abutment bar and the contacting member cooperating therewith.

Fig. 8 is a transverse sectional view taken upon the plane of line 8—8 of Fig. 7, and

Fig. 9 is a transverse sectional view taken on the plane of line 9—9 of Fig. 4.

In the above-mentioned drawings there has been shown but one embodiment of the invention which is now deemed preferable, but it is to be understood that changes and modifications may be made within the scope of the appended claims without departing from the spirit of the invention.

Briefly and in its preferred aspect, the invention may include, first, a base having a table movable preferably in a horizontal plane in two directions, there being a saddle member interposed between the machine base and the table, the saddle being movable in one direction on the base and the table being movable on the saddle in a direction at right angles thereto; second, a rotating tool such as a boring tool movable vertically on a fixed axis within a suitable spindle and head; third, bars mounted in the table and in the saddle built up of individual members and having spaced abutments thereon at precisely equal distances apart; fourth, contacting members mounted respectively in the base and saddle oscillatable into and out of engagement with the abutments on their respective bars; fifth, precision means for moving the contacting member for each of the abutment bars; sixth, means to indicate the positions to which the contacting members have been adjusted; seventh, zero setting means for the contacting members; eighth, clamping means for the table and saddle in any adjusted position; and ninth, clamping means normally holding the micrometer in clamped position.

Referring more in detail to the figures of the drawings, there has been shown a machine of the general type shown in the patent to Hanson 1,323,267 granted December 2, 1919, having a movable work mounting table, the positions to which the table is moved being determined to extremely high precision.

The present machine comprises a base 10 having a column 11 thereon supporting a vertically movable head 12 having a rotatable tool support-

ing and rotating spindle 13. Within the lower end of this spindle 13 may be mounted any suitable boring or other tool 14 adapted to engage work W mounted in fixed position on the table. Upon suitable horizontal ways 15 on the base 10 is a saddle member 16 movable toward and from the column 11 and upon the saddle 16 is mounted the work mounting table 17 movable upon suitable horizontal ways 18 in a direction at right angles to the direction of movement of the saddle. As these members 16 and 17 and their movements are or may be in every way similar to the members in the above-mentioned patent, it is not thought necessary to describe them more in detail. It will be understood also that there are provided manual means to move the saddle 16 toward and from the column 11 such as the screw 19 having the hand wheel 20 upon its forward end and for traversing the table 17 transversely along the saddle 16 by means of the screw 21 having a hand wheel 22 upon one end.

Positioning devices for the saddle 16 and for the table 17 are provided which are in every way duplicates of each other so that but one of these will be required to be described. One of these measuring or positioning devices determines the position of the saddle 16 in its movements toward and from the column 11 and the other positioning device determines the position of the table 17 upon the saddle 16. In the drawings details are shown of the positioning means for moving the table 17 on the saddle 16 and the description will be limited to these means. It will be understood that a duplicate positioning device will be employed to determine the movements of saddle 16 on the base 10.

Extending along the under side of the table 17 is a longitudinal recess within which are inserted elongated bars 23 forming a central channel or groove within which are inserted a plurality of blocks 24. The bars 23 with the blocks 24 supported between them are shown more particularly in Figs. 7 and 8. The inner lower surfaces of the elongated bars 23 are provided with a lateral extension upon which the lower surfaces of the blocks 24 may rest and at their upper periphery the blocks may contact directly with the surface of the recess within the table 17. Each of these blocks 24 at one end is formed with a short axial extension 25 of reduced diameter and at their opposite end with a head 26 fitting the surfaces of the bars 23 and of the recess, there being an intermediate head 27 on each block 24 so that the blocks are held accurately in axial alignment. At one end of the table 17 is inserted a metal block 28 against which one of the extensions 25 of the blocks 24 abuts and at the opposite end of the table 17 is inserted a member 29 having a spring pressed plunger 30 bearing against the head 26 of the block 24 at that end and constantly holding the row of blocks in closely abutted position. As the blocks 24 are of precisely equal length the end faces of the heads 26 form equally spaced abutments longitudinally along the table 17 in the direction of its movement on saddle 16 and are maintained in this position by the spring pressed plunger 30.

Lying within the saddle 16 and closely adjacent the recess within the table 17 for the blocks 24 is an elongated bar 31 having at its inner end a lateral projection 32 one face of which is adapted to contact with any one of the end faces or abutments of blocks 24. By oscillating this bar 31 about its axis to one angular position the contacting surface is in the position shown in full

lines in Figs. 7 and 8. This is the position assumed by the bar 31 while indicating the position of the table 17. In the position shown in dotted lines in Fig. 8 the rod 31 and its projection 32 have been oscillated from block contacting position to an inoperative position below the surface of the table 17 so that the table may be moved to any transverse position on the saddle 16 without injury to any part of the positioning mechanism.

At the right hand end of the elongated bar 31 and attached thereto through means presently to be more fully described, is a micrometer measuring device having a movable member 33. As shown most clearly in Fig. 3, this micrometer comprises the movable member 33 slidably mounted within a portion of the micrometer and having an internal threaded portion engaging the screw threads of the micrometer spindle 34. This movable member 33 is prevented from rotating during its sliding movement by engagement with a dovetail slide 35 formed in the saddle 16 on which it is freely movable at all times. Mounted in the micrometer bracket 36 is a dial indicator 37 the movable spindle 38 of which is in alignment with the micrometer spindle 34. Movement of the micrometer spindle 34 a limited distance axially within its rotating member 45 is permitted and moves the spindle 38 of the dial indicator 37 to rotate its pointer 40 in the usual manner.

To rotate the micrometer spindle 34 to move the member 33 and the elongated rod 31 to the left or right there is provided the hand wheel 39 mounted on rotating member 45 and normally held in clamped position but adapted to be released for rotation by oscillation of a small hand wheel 41 on the forward end of square shaft 42. The periphery of the hand wheel 39 fits between the abutments formed on a plunger 43 and a sleeve 44 housed within the bracket 36. The sleeve 44 is slidably mounted on an extension of the plunger 43 and is spring pressed toward the abutment on the plunger 43 by means of a light spring as shown. With the squared shaft 42 in the position shown in Fig. 3, the hand wheel 39 on the micrometer is clamped, but upon oscillation of the shaft 42 and hand wheel 41 through an angle of approximately 45° the plunger 43 and sleeve 44 are separated sufficiently to free the hand wheel 39 from frictional engagement with the adjacent faces of the plunger and sleeve to permit free rotation of the micrometer spindle 34 and axial movement of the member 33.

Mounted for rotation with the micrometer spindle 34 is the rotatable member 45 on which is mounted a large diameter dial 46 graduated to fractions of an inch such as ten thousandths. The rotatable member 45 surrounds and supports the slidable member 33 and is supported within the bracket 36 for rotation but maintained against endwise movement on suitable anti-friction bearings. The dial lies closely adjacent a plate 47 fixed in position upon the micrometer bracket 36 in a position concentric with the dial. A zero line on this plate 47 enables rotary positions of the dial 46 to be accurately determined. Rotation of the rotary member 45 and dial 46 adjusts the axial positions of the slidable member 33. This is for the reason that the rotary member 45 has splined within it the spindle 34 of the micrometer so that rotation of the hand wheel 39 rotates the spindle 34. Movement of the slidable member 33 also axially moves the elongated rod 31 to which member 33 is adjustably attached at one end.

To vary the adjustment of the bar or rod 31 relative to the slidable member 33 so that the distance between projection 32 and member 33 may be varied, rack teeth 48 may be cut into an extension 49 of the bar 31, these teeth being adapted to engage a pinion 50 on a short cross shaft 51 mounted within the slidable member 33. Rotation therefore of the cross shaft 51 by its hand wheel 52 will traverse the slidable member 33 to the right or left together with the parts attached thereto as will presently be described. To clamp the rod 49 in position relative to the member 33 a screw 52^a is provided threaded into the member 33 and engaging against the bar or rod 49.

Carried by the slidable member 33 is a pointer 53 the end of which lies adjacent a scale 54 secured in fixed position to the bracket 36 in which the micrometer is mounted. In order to facilitate reading the graduations of the dial 46 and the positions of the pointer 53 small lenses 55 and 56 may be inserted within the bracket directly above the reading positions respectively of the dial 46 and scale 54.

On the saddle 16 and extending in the direction of movement of the table 17 is a scale 57 extending preferably the entire length of travel of the table. This scale 57 is graduated throughout its length by inch or two inch indications only and is retained in fixed position in the saddle 16 by any preferred means (not shown). At one end the scale 57 may be graduated to small divisions for convenience in the preliminary adjustment of the positioning means on new pieces of work.

Closely adjacent the scale 57 fixed to the saddle 16 and on one side thereof is a short scale 58 fixed to and moving with the table 17; this short scale 58 as shown may preferably be graduated to small fractional parts of an inch. Also adjacent the fixed scale 57 and on the opposite side from the short scale movable with the table 17 is a slidable member or bar 59 carrying a zero indication 60 contacting with the scale 57. This member or bar 59 by its handle 61 may be moved to any position in a direction parallel to direction of the table 17 and closely adjacent the scale 57. Clamping means 62 for this rod 59 and an operating hand wheel 63 therefor are provided in the table 17.

As shown in Fig. 3 the rod 31 at one end is attached to a member 64 loosely but in a manner to rotate the rod when member 64 is rotated. Also member 64 is attached to a slidable intermediate member 65. Oscillation therefore of member 65 by its handle 66 will oscillate the rod 31 to move projection 32 into or out of engagement with the abutment surfaces of blocks 24. Preferably the connection between member 65 and the rod 49 permits oscillation between limits of the member 65 sufficient to move the projection 32 into or out of operative position without rotation of the rod 49.

In the operation of making precision adjustments of the table 17 the final adjustment is always toward the right as seen in the figures. When an abutment on a block 24 contacts with the projection 32 and further movement to the right takes place the rod 31 will be forced against member 64 and member 64 against member 65. Slidable member 33 will therefore be moved to the right and micrometer spindle 34 will move slightly to the right. The end, therefore, of the spindle 34 will abut against and move the spindle 38 of dial indicator 37 toward

the right. The movement of the table 17 may then be continued until the pointer 40 of dial indicator 37 moves around to its zero position. With the parts in these positions the adjustment of the table 17 to the position called for by the micrometer adjustment and the particular block engaged by the projection 32 is complete.

Manual means are provided to move the micrometer spindle 34, member 33 and parts attached thereto in a direction to force the spindle 34 against the end of indicator spindle 38. This means is in the form of a small lever 67 which oscillates its shaft 68 and forces plunger 69 axially in one direction. A spring 70 bearing against an end of the plunger 69 returns the plunger to initial position when lever 67 is released. Plunger 69 engages within a wide annular recess formed in the spindle 34 so that movement to the right of the plunger 69 will force the spindle 34 against dial indicator spindle 38. With the plunger 69 in the position shown in Fig. 3, which is the position assumed when the lever 67 is released, the micrometer spindle 34 may be moved to the right a limited distance when final adjustments of the table are being made for which reason the recess within which the plunger 69 fits is made of substantial width.

In the initial setting up of the positioning mechanism for operations upon a particular work piece the work piece is secured to the table 17 as shown at W. The work piece W may be lined up with reference edges thereon disposed parallelly to the directions of movement respectively of the table 17 and saddle 16. The position of any one of the zeros on scale 57 relative to the graduations on scale 58 is then noted. As the scale 57 is mounted on saddle 16 and is parallel to the rod 31 one of its zero lines may be employed to indicate the position of the projection 32. When a zero line of scale 57 is in alignment with a zero line on scale 58 the projection is closely adjacent one of the abutments on block 24. The scale 58 as shown in Fig. 5 indicates that the projection 32 is spaced axially from one of the abutments on blocks 24 a distance of three-quarters of an inch. To adjust the axial position of the projection 32 so that with the work piece W in position for its first operation the projection 32 will contact abutment on a block 24, hand wheel 52 is rotated to move rod 49 intermediate member 64 and the rod 31 toward the right. To determine the amount of this movement a scale is provided on member 65. The necessary adjustment is made when the graduation on the scale on member 65 in contact with its zero line corresponds to the graduation of scale 58 contacting with a zero on scale 57. The rod 49 can then be clamped by hand wheel 52^a so that rod 31 and parts attached thereto will move with the member 33 of the micrometer. With this adjustment completed the table 17 can be moved to the right until indicator 40 is over its zero in which the initial operation upon the work piece W can take place.

What I claim is:

1. Positioning means for the table of a machine tool comprising in combination, a support, a table movable thereon having abutments spaced equally in the direction of its movement, a micrometer on said support having its spindle parallel to the direction of movement of said table, a rod within said support connected to the spindle

of said micrometer and having a projection at one end thereof, means to oscillate said rod to move said projection into and out of abutment engaging position, and means to vary the axial adjustment between the micrometer spindle and the projection.

2. Positioning means for the table of a machine tool comprising in combination, a support, a table movable thereon, members having equally spaced abutments thereon mounted on and movable with said table, a rod mounted within the support for limited axial movement parallel to the direction of movement of the table, an abutment contacting projection at one end of said rod, a micrometer mounted on said support adjacent the opposite end of said rod and having its spindle in alignment with and connected to said rod, and means to adjust the axial position of said projection and rod predetermined distances toward and from said spindle.

3. Positioning means for the table of a machine tool comprising in combination, a support, a table movable thereon, members having equally spaced abutments thereon mounted on and movable with said table, a rod mounted within the support for limited axial movement parallel to the direction of movement of the table, an abutment contacting projection at one end of said rod, a micrometer mounted on said support at the opposite end of said rod and having its spindle in alignment with and connected to said rod, means to oscillate said rod to move said projection into and out of abutment engaging position, and means to adjust the axial position of said projection and rod predetermined distances toward and from said spindle.

4. Positioning means for the table of a machine tool comprising in combination, a support, a table movable thereon, members having equally spaced abutments thereon mounted on and movable with said table, a rod mounted within the support for limited axial movement parallel to the direction of movement of the table, an abutment contacting projection at one end of said rod, a micrometer mounted on said support adjacent the opposite end of said rod and having its spindle in alignment with and connected to said rod, an elongated scale on said support extending parallelly to the direction of movement of said table, a fixed zero indicia on said table, and means to adjust the axial position of said projection and rod predetermined distances toward and from said spindle.

5. Positioning means for the table of a machine tool comprising in combination, a support, a table movable thereon in a straight line, aligned abutting members having abutments thereon mounted on and movable with said table, said abutments being disposed transversely of said members and equally spaced axially thereof, an elongated rod mounted within the support for limited axial movement parallel to the direction of movement of the table, an abutment contacting projection at one end of said last mentioned rod, a micrometer mounted on said support at the opposite end of said rod and having its spindle in alignment with and adapted to contact said rod, and means to adjust the distance between said projection and the end of said rod contacting with said spindle.

JOHN M. RUSNAK.
